ATTORNEYS.

UNITED STATES PATENT OFFICE.

JOSEPH CARROLL SPARKS, OF MODESTO, CALIFORNIA.

RAZOR-BLADE HOLDER.

Application filed May 19, 1923. Serial No. 640,170.

To all whom it may concern:

Be it known that I, JOSEPH CARROLL SPARKS, a citizen of the United States, residing at Modesto, in the county of Stanislaus and State of California, have invented new and useful Improvements in Razor-Blade Holders, of which the following is a specification.

This invention relates to improvements in razor blade holders, the principal object of which is to provide a simple and efficient holder for a razor blade so that the same may be honed or stropped in an efficient manner.

Another object is to produce a device of this character which is cheap to manufacture and one well within the purchase price of the average user.

Other objects and advantages will be apparent during the course of the following description.

In the accompanying drawings forming a part of this specification, and in which like numerals are employed to designate like parts throughout the same,

Figure 1 is a perspective view of my preferred form of blade holder,

Figure 2 is a fragmentary view of a modified form, and

Figure 3 is a cross section taken on the line 3—3 of Figure 2.

Figure 4 is a cross section of my device showing the manner of retaining a Gillette-type of blade, and Figure 5 is a cross section similar to Figure 4 showing the manner of retaining an Eveready type blade.

Applicant is aware of the fact that various means have been employed for holding razor blades during the sharpening operation. These holders however, have been complicated, unwieldy and hard to adjust so that the blade could not be properly held.

I have therefore produced a holder which eliminates these difficulties.

In the accompanying drawings wherein for the purpose of illustration is shown a preferred embodiment of my invention, the numeral 5 designates a substantially U-shaped handle portion to one end of which is secured a flat portion 6 having a rim 7 formed thereon.

A similar downwardly extending rim 8 is

also secured to the flat portion 6, which rim is recessed so as to receive one end of a razor blade as shown at 9.

Lugs 11 are formed upon the lower edge of the flat portion 6 and are adapted to pass through the usual openings of the razor blade as best shown in Figure 1. In order to maintain the blade in its proper position in the holder I provide a slide 12 having a recessed nose 13 which is adapted to contact the blade. This slide has a finger-piece 14 movable in a groove 16 formed in a substantially U-shaped filler 17. This filler 17 fits within the U-shaped handle 5 and serves to retain a spring 18. This spring contacts the end of the slide 12 and is confined by a lug 19.

A band 21 is secured about the handle 5 and U-shaped portion 17 for the purpose of retaining the same in proper working relation. The modified form shown in Figure 2 is identical with that of Figure 1, with the exception that the lugs 11 are eliminated. This elimination provides for the accommodation of a razor blade having the thick re-enforcing metal at one edge thereof.

It will thus be seen that blades of various makes can be quickly placed within the holder by manipulating the finger-piece 14 which withdraws the slide 12 and that immediately upon release of the finger piece, the spring 18 will function to cause the slide 12 to engage the end of the blade forcing the opposite end of the blade into contact with the recess formed in the rim 8.

It is to be understood that the forms of my invention herewith shown and described are to be taken as preferred examples of the same, and that various changes in the shape, size and arrangement of parts may be resorted to without departing from the spirit of the invention or the scope of the subjoined claim.

Having thus described my invention, I claim:

A razor blade holder adapted to receive blades of various makes and comprising a handle, a flat portion formed on one end of the handle, a rim formed on the upper edge of the flat portion to receive one end of the blade, a slide having one end provided with a recess formed in its inner portion to

engage the blade, said slide being slidably mounted within the handle, a lug arranged in the handle midway its ends, a band surrounding the handle and adapted to retain said slide operatively associated therewith, a coil spring having its end convolutions engaging the lug and the adjacent end of the

slide respectively, means for reciprocating the slide against the tension of the spring to release the blade, and lugs formed on the flat portion for engaging the blade in the manner specified. 10

In testimony whereof I affix my signature.
JOSEPH CARROLL SPARKS.
